UNITED STATES PATENT OFFICE.

DAVID S. KENNEDY, OF BROOKLYN, NEW YORK, ASSIGNOR TO MERGENTHALER LINOTYPE COMPANY, A CORPORATION OF NEW YORK.

TYPOGRAPHICAL DISTRIBUTING MACHINE.

Application filed August 16, 1923. Serial No. 657,657.

To all whom it may concern:

Be it known that I, DAVID S. KENNEDY, a citizen of the United States, residing at Brooklyn, in the county of Kings and State 5 of New York, have invented certain new and useful Improvements in Typographical Distributing Machines, of which the following is a specification, reference being had therein to the accompanying drawing.

10 This invention relates to typographical machines, such as linotype machines of the general organization represented in U. S. Letters Patent to O. Mergenthaler, No. 436,532, wherein circulating matrices are released from a magazine in the order in which their characters are to appear in print and then assembled in line, the composed line transferred to the face of a slotted mold, the mold filled with molten metal to form a 15 slug or linotype against the matrices which produce the type characters thereon, and the matrices thereafter returned through distributing mechanism to the magazine from which they started.

20 25 There are now in use two distinct kinds of machines, one designed for the use of ordinary matrix fonts comprising ninety different characters suitable for the more usual composition or "straight" matter, and the other designed for special matrix fonts comprising only seventy-two characters suitable

30 35 for head letter and display work, etc. It is the object of this invention to provide a single machine capable of handling any of the ordinary matrix fonts or any of the special matrix fonts so that such machine may be used for any class of work desired. Such a machine is disclosed in either of my prior Letters Patent Nos. 1,397,974 and 1,

40 45 397,968. In the latter patent, the machine is equipped with two interchangeable distributor bars, one having ninety tooth-combinations to cooperate with the matrices of the ordinary fonts, and the other having seventy-two tooth-combinations to cooperate

50 55 with the matrices of the special fonts. In the former patent, a single distributor bar having ninety tooth-combinations is employed to cooperate with matrices of both kinds, but the tooth-combinations of the matrices of the special fonts are located in relatively different setwise positions throughout each set (as distinguished from the tooth-combinations of the ordinary fonts, which are arranged in the same set-

wise position throughout each set) in order to provide for the distribution of the matrices into the appropriate magazine channels.

The present invention contemplates a construction whereby the matrices of both the ordinary and special fonts may be distributed into their proper magazine channels from a single distributor bar, and this without involving any change in location of their tooth-combinations or any other change in form, except, of course, as to thickness. To this end, specifically, there is provided a pair of notched matrix sustaining rails to cooperate with the distributor bar and adapted to be moved into or out of operative position as required, either manually or automatically. These rails are maintained out of operative position when matrices of the ordinary or ninety character fonts are in use, so as to allow said matrices to drop directly from the bar in the usual manner for passage to their appropriate magazine channels but when matrices of the special or seventy-two character fonts are in use, the rails are maintained in operative position so as to afford temporary support to said matrices when released from the distributor bar and then drop them at other selected points for passage to their appropriate magazine 75 80 85 channels.

In the accompanying drawings, the foregoing improvements have been illustrated in connection with a shiftable multiple-magazine machine of the kind known in the trade as "Model 8," but it should be understood that they are equally applicable to machines of other kinds, including those of the single-magazine variety. In short, the invention is shown merely in preferred form and by way of example, and obviously many changes and modifications may be made therein and in its mode of adaptation without departing from its spirit.

Referring to the drawings:

Fig. 1 is a side view, partly in section, of the upper portion of a linotype machine equipped with the present improvements;

Fig. 1^a is a similar view showing a modification;

Fig. 2 is a detail section taken on the line 2-2 of Fig. 1, the distributor bar being shown in broken lines;

Fig. 3 is a front view, partly broken away,

of the distributing mechanism shown in Fig. 1;

Fig. 4 is a side view similar to Fig. 1 but showing the parts in a different condition; 5 and

Fig. 5 illustrates a further modification.

In the embodiment illustrated, the matrices X of the ordinary ninety character fonts are stored in the two upper magazines 10 A and A¹, which are provided with ninety-one grooved channels spaced apart in the usual way, while the matrices Z of the special seventy-two character fonts are stored in the lowermost magazine A², which is provided with but seventy-three grooved channels spaced apart in a different manner, an extra channel in each case being allotted to matrices bearing the letter "e". The several magazines are mounted in a shift-frame 15 which is arranged to be raised and lowered in the well known manner, so as to bring any selected one of the magazines into operative relation to the distributor comprising, as usual, the longitudinally ribbed or permuted bar B and the set of matrix conveying screws B¹. When either of the magazines A, A¹, is in operative position, the matrices X are conducted thereto from the distributor through the regular magazine entrance C; whereas, when the lowermost magazine A² is in operative position, the matrices Z are conducted thereto from the distributor through the special magazine entrance C¹. These two entrances differ in the number 20 and spacing of their matrix channels so as to correspond with the respective magazines, and are mounted so as to be interchangeable in position with each other for the purpose stated. The particular form of mounting 25 herein shown is fully described in my prior Letters Patent No. 1,397,972, to which reference may be had, so that no further explanation seems necessary.

As before stated, the present invention is 30 designed to provide for the distribution of the matrices of both the ordinary and special fonts from the distributor bar without involving any change in form of the matrices in the different fonts. In the specific embodiment illustrated, there is employed a pair of matrix sustaining rails D extending along the opposite sides of the distributor bar B and movable into or out of operative position, as required. When 35 the matrices X of a regular font are undergoing distribution, the two rails occupy an inoperative position so as to stand clear of such matrices and allow them to drop directly into the proper channels of the magazine entrance C for return to their corresponding magazine A or A¹, as the case may be. On the other hand, when the matrices Z of a special font are undergoing distribution, the rails occupy an operative position 40 so as to extend beneath the upper ears Z¹

of said matrices and give temporary support to the latter when they are released from the distributor bar. As best shown in Fig. 2, the rails D are formed on their inner edges with oppositely disposed notches d to permit the matrices Z to drop from the rails at selected points in the length thereof, there being as many such pairs of notches as they are matrix channels in the magazine A² and the cooperating magazine entrance C¹, or 45 seventy-three in all. As best shown in Fig. 3, the releasing points of the rails D, as determined by the notches d, are in most cases located beyond the releasing points of the distributor bar B, as determined by the particular tooth-combinations used in distributing the matrices Z, the whole arrangement being such that after the matrices Z have been released from the distributor bar B, they are carried forward varying distances 50 by the rails D and then dropped into the underlying channels of the magazine entrance C¹. In other words, the spacing of the rail notches is different from that of the bar combinations, the latter being spaced 55 apart in accordance with the spacing of the matrix channels of the magazine A or A¹ and the cooperating entrance C, and the former being spaced apart in accordance with the matrix channels of the magazine A² and the cooperating entrance C¹. In this connection, it may be noted that, as in my prior Letters Patent No. 1,397,974, the tooth-combinations on the matrices Z have 60 been rearranged to correspond with the different location of their magazine channels, as will be apparent from Fig. 3. The movement of the rails D into or out of operative position may be effected in any suitable manner, but in the present instance, it is 65 proposed to effect such movement automatically. Several different embodiments being shown by way of example.

In Figs. 1 to 4, one of the matrix sustaining rails D (the front one) is carried by a 70 pair of arms D¹ pivotally suspended from a horizontally disposed rod D² attached by brackets D³ to the distributor bar B. One of the arms D¹ is formed with a stop member D⁴ adapted to engage the front face of the distributor bar and locate the rail in its 75 proper position when in use. About midway of its length, the rail D is provided with a depending bar D⁵ arranged to be engaged by a projecting piece D⁶ secured to the front 80 plate of the magazine entrance C. As a result, when the entrance C is brought into action, as required for the distribution of the matrices X of the ordinary fonts, the rail D will be pushed forwardly out of the way (see 85 Fig. 4), so as to stand clear of the matrices X when they are released from the distributor bar. The other of the rails D (the rear one) is mounted directly upon the magazine entrance C¹ so as to be carried thereby into 90

and out of operative position. As will be observed, the magazine entrance C^1 is without the projecting piece D^6 , and hence when this entrance is brought into action for the 5 distribution of the matrices Z of the special fonts, both of the matrix sustaining rails will be located in operative position so as to carry out the distribution of the matrices Z in the manner before indicated (see Fig. 10 1), the front rail being located in its operative position by means of the stop D^4 , and the rear rail being located in its operative position directly by the entrance C^1 . When the entrance C^1 is later thrown out of 15 action, the rear rail will, of course, be carried along therewith and will remain out of operation until the entrance is again brought into use. The front rail, on the other hand, will occupy its operative position at all times 20 except when the magazine entrance C is in use.

In Fig. 5, the rear rail D , instead of being carried by the magazine entrance C^1 , is mounted on the distributor bar B like the 25 front rail, being carried by a pair of arms D^7 pivotally suspended from a transverse rod D^8 attached by brackets D^9 to the distributor bar. In this instance, the arms D^7 and D^9 of the two rails are provided with extensions D^{10} extending transversely across the distributor bar through a slot formed in its upper edge and connected together by a pin-and-slot connection D^{11} , so that the movement of one rail to and from operative position 30 effects a corresponding movement of the other rail. A spring D^{12} attached to the front rail tends constantly to hold the two rails in their inoperative position, but this tendency of the spring is resisted and overcome by means of a plate D^{13} carried by the 35 magazine entrance C^1 and adapted to engage the rear rail. Consequently when the magazine entrance C^1 is brought into action for the distribution of the matrices Z of the 40 special fonts, the two rails are moved to and maintained in their operative position, as required. When, however, the entrance C^1 is thrown out of action, the two rails are moved instantly to their inoperative position 45 under the influence of the spring D^{12} , so that when the other magazine entrance C is brought into action, the matrices X of the ordinary fonts may be distributed in the usual way without interference with the 50 rails.

In Fig. 1^a, both of the rails D are carried by the magazine entrance C^1 , and hence are located in or out of operative position according as that entrance is swung into or out of action. It will be understood that these 55 two rails are separated at their receiving ends so as to allow the matrices to pass onto the distributor bar without interference.

In all three embodiments above discussed, 60 the movement of the two matrix sustaining

rails is controlled by that of the magazine entrances. In Fig. 5, however, there is shown by dotted lines a modified arrangement of the parts by which the movement of the rails may be controlled by that of the magazines. According to this modification, the plate D^{13} may be omitted from the magazine entrance C^1 , and a similar plate D^{14} attached to the upper magazine in position to engage a bar D^{15} projecting downwardly from the front rail D , in such manner that when said magazine is moved into operative position, the matrix sustaining rails D , through the engagement of the plate D^{14} and bar D^{15} , will likewise be moved to operative position. In this case, however, the magazine A^2 , which contains the matrices Z of the special font, should be located at the top of the column in place of the magazine A . 85

While the foregoing improvements have been herein illustrated in connection with the regular and special fonts before described, it should be understood that they are equally applicable to other matrix fonts as well. For instance, in the commercial Model 22 machine, or as represented in my prior Letters Patent No. 1,397,967, the special seventy-two character matrix fonts are used interchangeably with other special fifty-five character fonts. To apply the present improvements to a machine of that kind, the distributor bar would only need to have seventy-three tooth-combinations to cooperate with the seventy-two-character fonts, and the matrix sustaining rails only fifty-five pairs of releasing notches to cooperate with the fifty-character fonts. In fact, the improvements would be useful in any machine in which it is desired to drop matrices directly from the distributor bar at one time and at different selected points at other times, it being possible to provide the rails with as many pairs of releasing notches as may be required for the particular purpose in view. Indeed, the rails might be formed with a single set of notches or with no notches at all, if the occasion should arise. In other words, the invention has been shown only in preferred form and by way of example, and as applied to the particular kind of machine described, but obviously many modifications and alterations therein and in its mode of adaptation will suggest themselves to those skilled in the art and still be comprised within its scope. 100

Having thus described my invention, its construction and mode of operation, what I claim and desire to secure by Letters Patent of the United States, is as follows:

1. A typographical distributing mechanism including, in combination, a distributor bar formed to release a matrix at one point, and cooperating means adapted to give support to said released matrix and 130

- drop it at a different point, said means being movable into or out of action, as required, according to the distributing point of the matrices undergoing distribution.
5. 2. A typographical distributing mechanism including, in combination, a distributor bar formed with a series of matrix releasing combinations, and cooperating means to give support to the released matrices and 10 drop them at other selected points, said means being movable into or out of action, as required, according to the distributing points of the matrices undergoing distribution.
15. 3. A typographical distributing mechanism including, in combination, a distributor bar, and a pair of matrix sustaining rails adapted to cooperate therewith and movable conjointly into or out of operative position, as required.
20. 4. A typographical distributing mechanism including, in combination, a distributor bar formed with a series of matrix releasing combinations, and a pair of matrix sustaining rails adapted conjointly to support matrices released from the bar and drop them at predetermined points, said rails being movable into or out of operative position, as required.
25. 5. A typographical distributing mechanism including, in combination, a distributor bar formed with a series of matrix releasing combinations, and a pair of matrix sustaining rails extending along the opposite sides of the bar and movable into or out of operative position, as required, said rails being notched at different points in their length and acting conjointly when in operative position to release the matrices at 30 corresponding points.
35. 6. In a typographical distributing machine adapted to be equipped with different sets of matrices, those of each set being provided at their upper ends with projecting ears, the combination of a distributor bar formed with a series of matrix releasing combinations, and a pair of matrix sustaining rails extending along the opposite sides of the bar, said rails being mounted so as 40 to be movable into or out of engaging relation to the matrix projecting ears, as required according to the set of matrices undergoing distribution.
45. 7. In a typographical distributing machine adapted to be equipped with different sets of matrices, those of each set being provided at their upper ends with projecting ears, the combination of a distributor bar formed with a series of matrix releasing combinations, and a pair of matrix sustaining rails extending along the opposite sides of the bar and movable into or out of engaging relation to the matrix projecting ears, as required according to the set of matrices undergoing distribution, said rails being 50
- notched at different points in their length so that when in operative position the matrices may drop therefrom at corresponding points.
55. 8. A typographical distributing mechanism including in combination, a distributor bar formed with a series of matrix releasing combinations, and a pair of matrix sustaining rails movable into or out of operative position, as required, and formed with a series of matrix releasing notches, the said notches being arranged directly opposite each other on the two rails and spaced apart differently from the bar combinations, for the purpose described.
60. 9. In a typographical machine adapted to be equipped with a magazine provided with matrix channels spaced apart in one manner, or with a magazine provided with matrix channels spaced apart in a different manner, the combination of a distributor bar common to said magazines, and means cooperating with said bar whereby the matrices may be distributed therefrom into either of the magazines to the exclusion of the other irrespective of the different spacing of their matrix channels.
65. 10. In a typographical machine, the combination of two magazines, one provided with matrix channels spaced apart in one manner, and the other provided with matrix channels spaced apart in a different manner, a distributor bar common to both magazines, means for establishing an operative relation between said bar and either of the magazines, and means cooperating with the distributor bar whereby the matrices may be distributed therefrom into the magazine in use to the exclusion of the other, irrespective of the spacing of its matrix channels.
70. 11. In a typographical machine, adapted to be equipped with interchangeable magazines provided with differently spaced matrix channels, the combination of a distributor bar formed with a series of matrix releasing combinations spaced apart in accordance with the spacing of the matrix channels of one magazine, a pair of matrix sustaining rails cooperating with said bar and formed with matrix releasing notches spaced apart in accordance with the spacing of the matrix channels of another magazine, and automatic means for moving the matrix sustaining rails into or out of operative position according to the magazine in use.
75. 12. In a typographical machine, the combination of two magazines provided with differently spaced matrix channels, means for selecting either of said magazines for use, a distributor bar formed with a series of matrix releasing combinations spaced apart in accordance with the spacing of the matrix channels of one magazine.

zine, a pair of matrix sustaining rails co-operating with said bar and formed with matrix releasing notches spaced apart in accordance with the spacing of the matrix channels of the other magazine, and automatic means for moving the matrix sustaining rails into or out of action according to the magazine in use.

13. In a typographical machine, the combination of two magazines provided with differently spaced matrix channels and movably arranged so that either may be brought into operative position, a distributing bar formed with a series of matrix releasing combinations spaced apart in accordance with the spacing of the matrix channels of one magazine, a pair of matrix sustaining rails cooperating with said bar and formed with matrix releasing notches spaced apart in accordance with the spacing of the matrix channels of the other magazine, and automatic means for moving the matrix sustaining rails into or out of action according to the magazine in use.

25 14. In a typographical distributing machine adapted to be equipped with interchangeable magazine entrances provided with differently spaced-apart matrix channels, the combination of a distributor bar formed with a series of matrix releasing combinations spaced apart in accordance with the spacing of the matrix channels of one magazine entrance, a pair of matrix sustaining rails cooperating with said bar and formed with matrix releasing notches spaced apart in accordance with the spacing of the matrix channels of the other magazine entrance, and means for moving the matrix sustaining rails into or out of action according to the magazine entrance selected.

ing of the matrix channels of another magazine entrance, and means actuated during the interchange of the magazine entrances for moving the matrix sustaining rails into or out of action according to the magazine entrance selected.

15. In a typographical distributing machine, the combination of two magazine entrances movably arranged so that either may be brought into operative position, a distributor bar formed with a series of matrix releasing combinations spaced apart in accordance with the spacing of the matrix channels of one magazine entrance, a pair of matrix sustaining rails cooperating with said bar and formed with matrix releasing notches spaced apart in accordance with the spacing of the matrix channels of the other magazine entrance, and means controlled by the movement of the magazine entrances for moving the matrix sustaining rails into or out of action according to the magazine entrance selected.

16. In a typographical machine, the combination of two matrix magazines, means for selecting either of said magazines for use, a common distributor bar formed with a series of matrix releasing combinations, a pair of matrix sustaining rails adapted to cooperate with said bar, and automatic means for moving said rails into or out of operative position according to the magazine selected.

In testimony whereof, I have affixed my signature hereto.

DAVID S. KENNEDY.
